US0D1052308S

(12) **United States Design Patent** (10) **Patent No.:** **US D1,052,308 S**
(45) **Date of Patent:** **** Nov. 26, 2024**

(54) **FOLDABLE LIFTING TABLE**

(71) Applicant: **Changzhou Neiaosi Smart Home Co., Ltd.**, Changzhou (CN)

(72) Inventor: **Yingchun Zhong**, Suqian (CN)

(73) Assignee: **Changzhou Neiaosi Smart Home Co., Ltd.**, Changzhou (CN)

(**) Term: **15 Years**

(21) Appl. No.: **29/941,691**

(22) Filed: **May 10, 2024**

(51) LOC (14) Cl. **06-03**

(52) U.S. Cl.

USPC **D6/655**

(58) **Field of Classification Search**

(57) **CLAIM**

The ornamental design for a foldable lifting table, as shown and described.

DESCRIPTION

FIG. 1 is a front perspective view of a foldable lifting table, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the foldable lifting table, which form no part of the claimed design.

1 Claim, 8 Drawing Sheets
